CLAIM

The ornamental design for a railing support block, as shown and described.

DESCRIPTION

FIG. 1 is a perspective view of a railing support block showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross section taken along lines 8—8 of FIG. 6;

and,

FIG. 9 is a perspective view showing a railing of the environment.

The broken lines depicting a railing and screws in FIG. 9 form no part of the claimed design.
